DRIVING MEANS IN EMBROIDERY MACHINES

Kurt Gustav Scheibel, Dresden, Germany, assignor to Wurker G. m. b. H., Dresden, Germany

Application May 25, 1934, Serial No. 727,561
In Germany June 3, 1933

19 Claims. (Cl. 112—86)

The present invention relates to an embroidery automatic machine such as forms the subject of prior application of A. A. Bohmann and K. G. Scheibel, Ser. No. 710,360, filed February 8th, 1934. 5 As is known in such arrangements the needle plates are displaced by the jacquard card and thereby interponents are influenced which finally transmit their adjustment to the rack bars which adjust the embroidery frame. The interponents must be moved. Such movement has 10 been effected from the driving mechanism of the machine. The movements of the interponents are comparatively complicated and must be carried out extremely exactly. For the production of these movements a cam drive has been utilized. The pin or follower running in a closed cam track can be positively exactly controlled and the cam can be formed exactly as required. 15 In order to increase the output of such embroidery machines it is usual to combine a large number of needles and corresponding embroidery frames in a single aggregate, as a result of which, constructions which are inconvenient and are very expensive are obtained. 20 25 As distinguished therefrom the present invention provides another method of increasing the output of such embroidery machines, namely the method otherwise usual in the art of increasing speed. The application of this method to embroidery machines was hitherto impossible because the cam guide in the transmission of movement prevented a high speed of rotation. The pins or followers running in the cams are pressed according to the construction of the interponents 30 to be moved first against the outer wall of the cam and then against the inner cam surface. As the result of rapid rotation such wear occurs that a change from the hitherto usual speed of rotation, (about 250 revolutions per minute) to high 35 speeds of rotation (about 500 revolutions per minute) is impossible. On the other hand the positive cam drive is particularly adapted to control the complicated motions of the interponents whereas other driving mechanism such as for 40 example lever drives or the like in consequence of the masses to be moved are quite unsuitable and also permit no separate control. 45

As distinguished therefrom the present invention resides in this that the motions of the intermediate members or interponents are transmitted from the coupling point of a crank link polygon. 50

In such a drive the members transmitting the movements are connected with one another simply by pivot pins or the like which can be mount- 55

ed solid and which at the most must be moved in straight guides so that even in the high speeds in question in automatic embroidery machines which are limited to a certain extent by the frame movement a continuously exact guide may be 5 maintained, the wear of the transmitting and moving means being kept throughout within normal limits. The masses to be moved may be kept very small and nevertheless a considerable stability imparted to the parts acting as bearings or 10 comparatively large bearing surfaces may be provided so that heavy loads can be taken up by the moving rods. In particular the use of this form of drive in embroidery machines is very convenient because in consequence of the movement of small masses stoppage can be effected 15 quite suddenly. The transmission of movement by this form of drive which is known in the art permits several interponents to be moved from one and the same coupling point since their 20 different types of movement requirements can be obtained by selection of a number of cams derived from the coupling point. This is particularly important in embroidery machines because in such machines quite a number of intermediate members have to move in quite different 25 ways, the separate movements bearing a definite time relation to one another. This can all be obtained by corresponding careful selection of the cams in question, the drive being considerably 30 simplified so that one and the same coupling point can be used for the movement of several intermediate members. 35

For the movement of these members it is moreover of importance that they should remain 40 stationary for certain times which do not correspond with the times of natural reversal in crank and connecting rod gearing. For example in order to contact the needle plates the movement of the feeler member, the reciprocation of which can take place in a shorter time than the half crank pin angular movement (180°) is necessary. As the plates will be engaged if possible at the beginning of the position of rest 45 in order to avoid damage and the reciprocating movement of the feelers can only correspond with the end positions of the crank pin movement, the problem is to interpose a pause in the interval between the two dead point positions of the crank pin carrier. These and such problems can 50 be solved by the drive of the present invention by selecting a stoppage of the transmission at a suitable moment between the two reversal points of the crank pin drive by suitable selection of a cam groove and the corresponding displacement 55

of the pivot of the transmission rods pivoted to the crank pin.

It may be remarked that similar controlling means are necessary for knitting machines as for 5 embroidery automatic machines and for this reason the drive of the invention is also suited for this type of machine. The driving means in accordance with the invention is suitable for any form of intermediate drive. It is however 10 particularly intended for a construction such as shown in the prior application No. 710,360 above mentioned; the drive is illustrated in conjunction with this construction in one embodiment 15 of the accompanying drawings.

Fig. 1 shows a vertical transverse section 16 through the device.

Fig. 2 is a vertical longitudinal section on the line II—II of Fig. 1.

Fig. 2a is a detail showing a modification.

Fig. 3 is a vertical longitudinal section on the line III—III of Fig. 1.

Fig. 4 is a vertical longitudinal section on the line IV—IV of Fig. 1.

Fig. 5 is a part of Fig. 3 to enlarged scale.

Fig. 6 is a vertical transverse section on the line VI—VI of Fig. 5.

Fig. 7 is a diagrammatic illustration of the drive employed.

The two automatic casings are indicated by 30 A and B as in the said prior application. In the casing A is mounted at 1 and 2 the shaft 3 which in order that the parts behind it will be visible is partly broken away. In the part broken away the shaft is indicated in dotted lines. On the 35 shaft 3 is mounted the bevel pinion 4 which meshes with a bevel pinion 5. The bevel pinion 5 is mounted on the main driving shaft 7 which appears also in the said prior application. On the shaft 3 is mounted the eccentric disc 8 which 40 is surrounded by the eye 9' formed as a bearing of the coupling rod 9. The coupling rod 9 is connected by the pivot 10 to a guide member 11 which is movable in an arcuate guide 12. It should be noted that the guide block 11 and the 45 arcuate guide 12 may be replaced by a link 13 as in Fig. 2a, the pivot 14 of which would be positioned at the point where the centre of curvature of the arcuate guide 12 would be if the guide 12 were used.

The two links 16 and 17 are connected to the 50 coupling rod 9 by means of the pivot 15. The link 16 is connected at the other end with a pivot 18 which is provided on the lever 20 mounted in bearings at 19. To the pivot 18 is also connected 55 the link 21, the other end of which is connected with the lever 23 by the pivot 22. The lever 23 forms the horizontal arm of a frame 24 shown in Fig. 1 which is adapted to swing by means of the pivots 25 and 26 in the housing in the direction 60 of the arrow indicated in Fig. 2. The upper end of the frame forms a cross bar by means of which the plates are always returned to the initial position after they have been contacted.

The link 17 is connected by means of the pivot 65 27 to the lever 29 mounted at 28 in the casing A. To this lever is pivoted at 30 the connecting rod 31 which is connected by the pivots 32 and 33 with the two U-shaped bails 34, 35. The U-shaped bails 34, 35 are mounted in the housing 70 at 34', 35' and carry the spindles 39 for the T-shaped levers 37, 37' or 38, 38' which are indicated by the same reference numerals in the said prior application. The mode of operation of the gearing connected with the levers 37 is already described in the earlier application and it

does not form the subject of the present application. Only the rods 51, 51', 51'', 51''' and 52, 52', 52'', 52''' which are connected with the carriages 53 carrying the switch need be mentioned. These carriages are as has been already 5 explained in said prior application mounted so as to be vertically movable in the housing B. On the carriages 53 are mounted the slides 59 to which the rack bars 61 are pivoted. The rack bars 61 cooperate through the pinions 68 with 10 the rack bars 110 which move the embroidery frame movably mounted on the table 102.

The carriages are driven from the shaft 40 mounted in the housing B which shaft is driven by an intermediate gearing (not shown) from 15 the main driving shaft 7. On the shaft 40 is mounted an eccentric disc 41 which is embraced by the eye 42' of the intermediate member 42 formed as a coupling rod. The double armed lever 44 is connected at 43 to the coupling rod, 20 said lever being pivoted at 45 in the housing B. The free end of the lever 44 is connected by the link 46 with the carriage 53. From this coupling 42 serving as a connecting rod the rack bars 61 and the locking pawl 69 are operated. 25 For this purpose the link 71 is connected to the coupling rod 42 at 70, being connected at the other end by the pivot 72 with a cam block 73. The cam block is guided in a cam track 75 provided on the wall 74 of the frame. To the pivot 30 72 is also connected the link 76 which is connected by the pivot 77 with the free arm of the bell crank lever 78 carrying the locking pawl 69. On the pivot 79 on which the bell crank lever 78 is secured is also mounted an arm 80 which 35 with a pin 81 engages in a slot 61' of the rack bar 61.

The card cylinder 106 over which the jacquard 40 158 is guided will be explained with reference to the Figs. 2-6. The spindle 106' of the card cylinder is mounted in a bearing member 147 which is movable on the slide bar 148 mounted on the machine frame. The plate 149 (Fig. 5) is mounted on the free end 115' of the bell crank lever 115 which plate embraces with a corresponding 45 eye the disc 150. The disc 150 also embraces with an eccentric opening the spindle 106' of the card cylinder 106. Moreover there is secured to the disc 150 hand lever 151. In the position shown in Fig. 5 the lever 151 is pressed against a pin 155 50 secured on the plate 149 and thereby determines the end position of the disc 150 or of the hand lever 151. If the lever 151 is swung to the right in the direction of the arrow shown in Fig. 5 then after overcoming the dead point position the 55 hand lever 151 bears against the stop pin 156 provided on the plate 149. At the same time however the spindle 106' of the card cylinder 106 is so displaced relative to the plate 149 that the pins 106'' of the card cylinder 106 come into 60 engagement with the jacquard card 158 held in the guides 157 (see the full line position Fig. 3 and the dotted line position Fig. 5).

By this arrangement it is possible without 65 having to release in any way the rods of the card cylinder 106 to push back the card cylinder for the purpose of changing the cards from the card guide 157 and bring it back into position.

The card cylinder 106 is driven by means of a worm 159 which meshes with a worm wheel 160 70 rigidly mounted on the cylinder spindle 106'. The worm 159 is mounted on the spindle 161 which runs at one end in bearing 162 in the housing A and at the other in the downwardly projecting bracket 147' of the movable bearing mem- 75

ber 147. A slot 163 is provided on the bracket 147 for the spindle 161. In order to ensure that the worm 159 is always in engagement without play with the worm wheel 160 the spindle 161 is pressed upwards resiliently by the spring bolts 164. A collar 165 on the spindle 161 ensures that the spindle 161 is connected so as to be axially movable with the bracket 147.

On the spindle 161 is mounted the pinion 166 with which the rack bar 167 cooperates. The rack bar 167 is guided so as to be vertically movable in the bearings 168. On the lower end of the rack bar shaft 167 is provided a bolt 169 which is embraced by the forked end 170' of a lever 170. The lever 170 is adapted to swing about the pivot 171 on the housing A and is provided with a slide guide 172 in which the eccentric disc 173 formed as a three-sided arc engages. The eccentric disc 173 is secured to the driving shaft 3 indicated in Fig. 1.

On the spindle 161 is also mounted an arm 175 which is provided with the locking bolt 176. This locking bolt cooperates with a locking disc 177 provided on the machine frame which is provided with one or more holes 178 corresponding to the locking bolt 176.

As the arc 173' of the arcuate cam is curved about the axis of the shaft 3 the lever 170 and the rack bar 167 connected therewith remains at rest as long as the corresponding arcuate member 173' remains in engagement with the slide member 172. During this time the pinion 166 is moved so far out of the plane of the rack bar 167, dotted position in Fig. 4, that the rack bar 167 is out of engagement with the pinion 166. During this time the pin 176 is located in one of the openings 178 of the locking plate 177 so that the spindle 161 is held against rotation. Before the end point of the cam portion 173' meets the slide portion 172 the lever 115 is turned in a manner later to be described, in the direction of the arrow indicated in Fig. 4 and thereby the card cylinder 106 is brought with the card guide 157 into the position shown in Fig. 4. At the same time however the bearing member 147 is also correspondingly moved to the right in the direction shown in Fig. 4 so that the spindle 161 reaches such a position that the pinion 166 is in mesh with the rack bar 167 and the pin 176 comes out of engagement with the opening 178, (full line position in Fig. 4). The pinion 166 mounted on the spindle 161 is thus now coupled with the rack bar 167 so that in turning the lever 170 upwards a rotation of the spindle 161 and corresponding rotation of the card cylinder 106 takes place in the direction of the arrow indicated in Fig. 4. As soon as the lever 170 has reached its upper dead point position, the lever 115 is again swung back. The card cylinder 106 is thereby moved with the card guide 157 to the plate needles 200 (see dotted position in Fig. 4), and at the same time the spindle 161 is axially displaced so that the pinion 166 comes out of engagement with the rack bar 167 and the pin 176 comes into engagement with the hole 178 of the locking disc 177. As the lever 170 in its upper dead point position also remains during about 60° angular rotation of the disc 173 in the position of rest, enough time is available for carrying out this operation.

During the succeeding downward movement of the swinging lever 170 the rack bar 167 remains out of engagement with the pinion 166 because the card cylinder 106 still remains held in position shown in Fig. 3. Only when the cam portion 173' again contacts with the lower slide guide

member 172 is the lever 115 again swung in the direction of the arrow in Fig. 3 as the result of which the card cylinder 106 and the parts connected therewith are again moved to the right so that the pinion 166 again comes into engagement with the rack bar 167. The operation can then be repeated.

The bell crank lever 115 is actuated also by the coupling member 9. For this purpose there is provided on the coupling rod 9 a bracket 9'' to a pivot 82 on which the link 83 is connected, which link is connected by a pivot 84 with a further link 85. The link 85 is mounted to swing at 86 in the housing. To the link pivot 84 is connected also the link bar 87 which is connected to the free end of the bell crank lever 115 by the pivot 88. The couple drive actuating the contacting rods for the needle plates, the needle plate return device 24 and the jacquard card cylinder mounting control mechanism is illustrated diagrammatically in Fig. 7 in which all the auxiliary mechanism has been omitted. The eccentric disc is shown as a crank 8 which is mounted on the spindle 3. To the coupling rod 9 which is pivotally connected at 10 with the rocking member 13 pivoted at 14 is connected by means of the bracket 9'' (shown in Fig. 3) a pivot 82 which during rotation of the crank 8 describes the curve indicated as a in dotted lines in Fig. 7. The link 83 is so arranged that while the pivot 82 moves on the cam portion curved to the arc b the pivot 84 remains stationary. This means however that the rods 87, 88, 115 connected with the pivot 84 are also stationary.

The pivot 15 also provided on the coupling rod 9 during the rotation of the crank 8 describes the curve indicated by c in Fig. 7. The link 16 connected to the pivot 15 is now so arranged that while the pivot moves through the cam portion shaped to the arc d the point 18 is stationary. This also involves stoppage of the driving members 20—24 connected with the point 18.

To the pivot 15 is connected also the links 17 which is so arranged that while the point 15 traverses the cam portion shaped to the arc e the pivot 27 is stationary. As a consequence the driving members 29, 31 connected with the pivot remain stationary during the corresponding time.

With reference to the coupling point 15 it is interesting that from it two different movements are initiated since two cam portions are used of the curve described by the point 15 and to these cam portions are provided correspondingly mounted links. As regards the drive initiated from the coupling member 42 it should be noted that the block 73 is formed after the manner of a shuttle, the cam portions indicated by Y and Z of the cam guide 75 being of arcuate form and having a radius of the length of the links 76. While the block 73 is moved in the cam portion indicated by Y the link 76 has only a swinging movement about the pivot 77 so that during the whole time the locking pawl 69 is held in engagement with the pinion 68 and the rack bar 61 is held out of engagement. If then the guide block 73 moves out of the cam portion Y passing through the cam portion between the two cam portions Y and Z the link is displaced at the same time during this swinging movement so that the pivot 77 moves into the dotted position. The lever 78 is thereby also moved at the same time into the dotted position so that the locking pawl 69 is brought out of engagement with the pinion 68, while the rack bar 61 is moved upwards towards the pinion. While the guide block 73 is guided

in the cam portion Z first to the right and then again to the left, the rack bar 61 remains in engagement with the pinion 68 and is only brought out of engagement when the cam block 73 moves from the cam portion Z to the cam portion Y.

5 I claim:

1. An automatic mechanism for embroidery machines and the like comprising a card cylinder, 10 needle plates operated by said card cylinder, a frame movement adjusting mechanism, means controlled by said needle plates controlling the operation of said frame movement adjusting mechanism, means for restoring said needle plates, and an oscillating lever actuating said 15 means controlled by said needle plates, said card cylinder and said restoring means.

2. An automatic mechanism for embroidery machines and the like comprising a card cylinder, 20 needle plates operated by said card cylinder, a frame movement adjusting mechanism, means controlled by said needle plates controlling the operation of said frame movement adjusting mechanism, means for restoring said needle plates and an eccentrically operated lever actuating said 25 means controlled by said needle plates, said card cylinder and said restoring means.

3. An automatic mechanism for embroidery machines and the like comprising a card cylinder, 30 needle plates operated by said card cylinder, a frame movement adjusting mechanism, means controlled by said needle plates controlling the operation of said frame movement adjusting mechanism, means for restoring said needle plates, an oscillating lever actuating said means 35 controlled by said needle plates, said card cylinder and said restoring means and means controlling the throw of said oscillating lever.

4. An automatic mechanism for embroidery machines and the like comprising a card cylinder, 40 needle plates operated by said card cylinder, a frame movement adjusting mechanism, means controlled by said needle plates controlling the operation of said frame movement adjusting mechanism, means for restoring said needle plates, an eccentrically operated oscillating lever 45 actuating said means controlled by said needle plates, said card cylinder and said restoring means and a cam shaped slide controlling the throw of said lever.

5. An automatic mechanism for embroidery machines and the like comprising a card cylinder, 50 needle plates operated by said card cylinder, a frame movement adjusting mechanism, means controlled by said needle plates controlling the 55 operation of said frame movement adjusting mechanism, means for restoring said needle plates, and an oscillating double-armed lever actuating said means controlled by said needle plates, said card cylinder and said restoring 60 means.

6. An automatic mechanism for embroidery machines and the like comprising a card cylinder, 65 needle plates operated by said card cylinder, a frame movement adjusting mechanism, means controlled by said needle plates controlling the operation of said frame movement adjusting mechanism, means for restoring said needle plates and an eccentrically operated double-armed lever 70 actuating said means controlled by said needle plates, said card cylinder and said restoring means.

7. An automatic mechanism for embroidery machines and the like comprising a card cylinder, 75 needle plates operated by said card cylinder,

a frame movement adjusting mechanism, means controlled by said needle plates controlling the operation of said frame movement adjusting mechanism and unitary oscillating means actuating said means controlled by said needle plates and said card cylinder.

8. An automatic mechanism for embroidery machines and the like comprising a card cylinder, 10 needle plates operated by said card cylinder, a frame movement adjusting mechanism, means controlled by said needle plates controlling the operation of said frame movement adjusting mechanism and an eccentrically operated double armed lever actuating said means controlled by said needle plates and said card 15 cylinder.

9. An automatic mechanism for embroidery machines and the like comprising a card cylinder, 20 needle plates operated by said card cylinder, a frame movement adjusting mechanism, means controlled by said needle plates controlling the operation of said frame movement adjusting mechanism, an eccentrically operated double armed lever actuating said means controlled by said needle plates and said card 25 cylinder and means controlling the throw of said lever.

10. An automatic mechanism for embroidery machines and the like comprising a card cylinder, 30 needle plates operated by said card cylinder, a frame movement adjusting mechanism, means controlled by said needle plates controlling the operation of said frame movement adjusting mechanism, an eccentrically operated double armed lever actuating said means controlled by said needle plates and said card 35 cylinder and cam means controlling the throw of said lever.

11. An automatic mechanism for embroidery machines and the like comprising a frame, 40 means for adjusting said frame, means for determining the amount of adjustment to be given to said frame and an eccentrically operated lever controlling said means for adjusting said frame and said means for determining the amount of 45 adjustment to be given to said frame.

12. An automatic mechanism for embroidery machines and the like comprising a frame, 50 means for adjusting said frame, means for determining the amount of adjustment to be given to said frame, an eccentrically operated lever controlling said means for adjusting said frame and said means for determining the amount of adjustment to be given to said frame and cam means controlling the throw of said lever. 55

13. An automatic mechanism for embroidery machines and the like comprising a frame, 60 means for adjusting said frame, means for locking said adjusting means, means for determining the amount of adjustment to be given to said frame including a reciprocating carriage and a double-armed eccentrically operated lever controlling said means for adjusting said frame, said means for locking said adjusting means and said reciprocating carriage. 65

14. An automatic mechanism for embroidery machines and the like comprising a frame, means for adjusting said frame, means for locking said adjusting means, means for determining the amount of adjustment to be given to said frame 70 including a reciprocating carriage, a double-armed eccentrically operated lever controlling said means for adjusting said frame, said means for locking said adjusting means and said reciprocating carriage and cam means cooperating 75

- with said lever controlling the amount of throw of said lever.
15. An automatic mechanism for embroidery machines and the like comprising a card cylinder, needle plates operated by said card cylinder, a frame movement adjusting mechanism, means controlled by said needle plates controlling the operation of said frame movement adjusting mechanism, means for restoring said 10 needle plates, an oscillating lever actuating said means controlled by said needle plates, said card cylinder and said restoring means and means for varying the amount of actuation given by said oscillating lever to said card cylinder.
- 15 16. An automatic mechanism for embroidery machines and the like comprising a card cylinder, a spindle for said card cylinder, an eccentrically operated lever moving said card cylinder to and fro, a gear carried by said spindle, an 20 axially movable drive shaft and a gear carried by said drive shaft maintained always in engagement with said gear upon said spindle.
17. An automatic mechanism for embroidery machines and the like comprising a card cylinder, a spindle for said card cylinder, an eccentrically operated lever moving said card cylin- 25
- der to and fro, a gear carried by said spindle, an axially movable drive shaft, a gear carried by said drive shaft maintained always in engagement with said gear upon said spindle, a second gear carried by said drive shaft and a reciprocating rack for driving said second gear. 5
18. An automatic mechanism for embroidery machines and the like comprising a card cylinder, a spindle for said card cylinder, movable bearings in which said spindle is mounted and eccentric means for varying the position of said 10 card cylinder with respect to said bearings.
19. An automatic mechanism for embroidery machines and the like comprising a card cylinder, a spindle for said card cylinder, movable 15 bearings in which said spindle is mounted, eccentric means for varying the position of said card cylinder with respect to said bearings, a drive shaft, means upon said drive shaft for rotating said cylinder, a gear carried by said 20 drive shaft, means for intermittently operating said drive shaft by said gear and means for locking said drive shaft when said gear is not being operated.

KURT GUSTAV SCHEIBEL. 25
